UNITED STATES PATENT OFFICE.

ALFRED D. RATHBONE, OF GRAND RAPIDS, MICHIGAN.

ELECTRIC FIREPLACE.

No. 902,008.

Specification of Letters Patent.

Patented Oct. 27, 1908.

Application filed February 4, 1908. Serial No. 414,234.

To all whom it may concern:

Be it known that I, ALFRED D. RATHBONE, a citizen of the United States of America, residing at Grand Rapids, in the county of Kent and State of Michigan, have invented certain new and useful Improvements in Electric Fireplaces; and I do hereby declare the following to be a full, clear, and exact description of the invention, such as will enable others skilled in the art to which it appertains to make and use the same.

My invention relates to improvements in electric fire places, and its object is to provide a device adapted to close the front of the usual form of a grate or fireplace, to provide means for supporting and properly utilizing electric heaters in place of the usual fuel, and to provide the device with various new and useful features hereinafter more fully described and particularly pointed out in the claims.

My device consists essentially of a frame or panel adapted to close the front of an ordinary fire place or grate and having therein a recessed reflector within which is supported the electric heaters, means for adjustably supporting the heaters within the same and a readily detachable base or crown portion to said device whereby access is easily had to the heater sockets for the purpose of wiring or adjusting the same, as will more fully appear by reference to the accompanying drawings, in which:

Figure 1 is a front elevation of a device embodying my invention; Fig. 2, a vertical section of the same on the line 2—2 of Fig. 1; Fig. 3, a horizontal section of the same on the line 3—3 of Figs. 1 and 2; Fig. 4, a detail in front elevation; and Fig. 5, a detail in vertical section on the line 5—5 of Fig. 1.

Like numbers refer to like parts in all of the figures.

The upper part of the panel consists of a transverse and forwardly projecting head 1 prolonged downward at each side by pilasters 2 secured thereto at their upper ends by overlapping extensions 16 and bolts 7. 3 represents a detachable base or "crown" member extending across between the lower ends of the pilasters 2 and detachably secured thereto by means of hooks 9 on the base, engaging hooks 10 on the pilasters. These described parts at their margins are of dimensions to fit the opening of an ordinary fireplace or grate and surround an opening

back of which and closing the same is a detachable reflector attached by bolts 8 extending through a flange 15 on the reflector and through the head 1 and pilasters 2. This reflector has concave margins 4 and a series of vertically extended concave portions 5 near the axis of each of which latter is arranged an electric heater (not shown). At the bottom of this reflector is a forwardly extended portion 17 through openings in which project sockets 6 for receiving and supporting the electric heaters. To adjust the heaters properly in front of the respective concaves 5, the sockets 6 are mounted on a bar 11 supported upon brackets 12, which latter extend forward and upward, and are adjustably secured to downwardly projecting lugs 13 beneath the front edge of the portion 17, by means of bolts 14 extending through vertical slots in brackets 12. A flange 18 on the rear of the base 3, closes the space between the same and the lower edge of the reflector.

What I claim is:

1. An electric fireplace, comprising a forwardly projecting head, a pilaster extending downward at each side, a detachable base, the same forming a structure surrounding a central opening and adapted in outline to fit the opening of an ordinary grate or fireplace, a concave reflector at the rear of said opening and closing the same, and means for supporting one or more electric heaters in front of said reflector and within said opening.

2. In an electric fireplace, a structure adapted to fit within the opening of an ordinary fireplace or grate and having a central opening, a reflector attached thereto and closing said opening, said reflector having concave margins and a series of concave recesses, and means for supporting an electric heater in front of each of said recesses and in the axis thereof.

3. In an electric fireplace, a structure adapted to fit within the opening of an ordinary fireplace or grate, and having a central opening, a detachable base beneath said opening, a concave reflector back of said opening and having a forwardly projecting lower margin provided with one or more openings, a bar supported below said margin, and sockets supported on the bar and projecting through said openings, and also adapted to receive and support electric heaters.

4. In an electric fireplace, a forwardly pro-

jecting head, a pilaster at each side and attached to the head, a base connecting the lower ends of the pilasters, hooks on the pilasters, hooks on the base engaging the first named hooks, a reflector having forwardly projecting margins attached to the head and pilasters, and also having a forwardly projecting lower margin provided with openings, a bar beneath said openings, brackets supporting the bar and adjustably attached to lugs on the said lower margin, and sockets supported on the bar and projecting through said openings, and also adapted to receive and support electric heat-
ers.

5. An electric fireplace, comprising a reflector having concave margins and a series of concave recesses, the lower margin of the same having a series of openings, downwardly projecting lugs on the said lower margins, a bar beneath said openings, brackets supporting the bar and extending forward and upward therefrom, said upward portions engaging the lugs and provided with vertical

slots, and screws inserted in said slots and in the lugs.

6. An electric fireplace, comprising a forwardly projecting head, a forwardly projecting base, pilasters connecting the head and base and detachably connected to the base, a reflector having concave margins attached to the head and pilasters, and also having a series of concave recesses, a forwardly extended bottom portion on the reflector and having a series of openings opposite the respective concave recesses, lugs on the lower edge of the reflector, brackets adjustably attached to the lugs, a bar supported by the brackets, and sockets supported on the bar and extending through the said openings in the reflectors.

In testimony whereof I affix my signature in presence of two witnesses.

ALFRED D. RATHBONE.

Witnesses:

GEORGINA CHACE,
LUTHER V. MOULTON.
